UNITED STATES PATENT OFFICE

DAVID H. BROWN, OF GRAND RAPIDS, MICHIGAN, ASSIGNOR TO CENTURY FURNITURE COMPANY, OF GRAND RAPIDS, MICHIGAN, A CORPORATION OF MICHIGAN

DESIGN FOR A CHAIR

Application filed October 28, 1930. Serial No. 37,419. Term of patent 7 years.

To all whom it may concern:

Be it known that I, DAVID H. BROWN, a citizen of the United States, residing at the city of Grand Rapids, in the county of Kent and State of Michigan, have invented a new, original, and ornamental Design for Chair, of which the following is a specification, reference being had to the accompanying drawings, forming a part thereof.

Fig. 1 is a perspective view of a chair showing my new design.

Fig. 2 is an enlarged fragmentary elevation of the top portion of the leg and joining parts.

Fig. 3 is an enlarged fragmentary elevation of the forward part of the chair arm, and

Fig. 4 is a plan view of the portion shown in Fig. 3.

I claim:

The ornamental design for a chair, as shown.

DAVID H. BROWN.
